UNITED STATES PATENT OFFICE

KURT REINHOLD, OF NEW YORK, N. Y.

APPAREL-LOCKING DEVICE

Application filed January 31, 1929. Serial No. 336,386.

The main object of this invention is to provide a device for securely locking articles of apparel, such as a coat, a cane, a valise and a hat, upon a suitable rack so that no unauthorized person may remove these articles after the device is sprung into locked position, unless the person is in possession of a key which releases the locking mechanism.

10 Another object of this invention is to provide a device which will secure a valise, a cane, and articles of apparel, such as a coat and a hat, upon a rack in such manner that key-operated means must be used to release these articles for their further use.

Still another object of this invention is to provide a coin operated mechanism for releasably securing articles of apparel or traveling necessities upon a rack, and key-operated means for releasing the locking mechanism when removing the articles.

The above and other objects will become apparent in the description below, in which characters of reference refer to like-named parts in the drawing.

Referring briefly to the drawing, Figure 1 is a front elevational view of the device.

Figure 2 is a side elevational view of the device, showing the locking tongue in full lines in securing position, and the same member in dotted lines in released position.

Figure 3 is a rear elevational view of the housing of the device with the rear cover removed to expose the coin-operated mechanism for releasing the locking tongue. Said view shows the mechanism in the position it assumes when the locking tongue is secured.

Figure 4 is a view similar to Figure 3, showing the coin-operated mechanism in released position.

Referring in detail to the drawing, the numeral 10 indicates a dished-out housing which has a flat face. The face of this housing has several elements mounted thereon. On the lower end of the face a bracket 11 has a pair of studs 12 and 13 projecting angularly and upwardly therefrom. These studs are provided with spring-projected depressible pins 14 imbedded in bores in the outer extremities of the studs whose purpose will be

more fully hereinafter described. Mounted above these studs is a support arm 15 which is provided with a slot 16 extending longitudinally from its base to a position midway of its length. In this slot a substantially semi-circular tongue 17 is mounted on a stud 18 and is normally retained in the position shown in broken lines in Figure 2 by a resilient finger 19. Extending at an angle downwardly from the tongue, below the axis of the pin 18, is a leg 20. This leg is unitary with the tongue 17 and swings as a unit therewith, assuming the position shown in broken lines in Figure 2 when the locking mechanism is released. This leg 20 is curved at its lower end in the direction of the studs 12 and 13 and is provided with a rubber or bakelite bumper pad 21, which latter is adapted to depress the depressible pins 14. A blunt, flat-headed extension 22 projects from the curved arm toward the casing 10 and enters into this casing through an aperture 23. This aperture is of sufficient size to permit the traveling of the extension as the support arm and leg swing from the locked to the released position, these positions being shown in full lines and in dotted lines. The leg 20 is provided with a rearwardly extending prong 24 which is slenderly curved and is adapted to enter into the opening in a bifurcated fork 25. The opening in the bifurcated fork is adapted to receive any one of the links 26 of a chain which has its opposite end suspended from an eyelet 27 and is adapted to be trained through the handle of a valise or similar other traveling appurtenance for the purpose of securing this member so that it cannot be removed.

The casing consists of a flat upper plate, indicated by the numeral 10, which is provided with bounding walls 28 and 29. At the upper ends of these walls, the casing is bulged outwardly. One of these bulges has a coin slot 29 located therein. This coin slot 29 permits the inception of a coin 30 which drops through a channel guarded by guide plates 31 and, after falling, comes to rest upon a lug 32 which has one of its ends tapered off. Behind the guard plate 31, and located in a recess provided for the purpose,

is a bell crank 33 pivoted at the intersection of the arms on a stud 34. The downwardly projecting arm of the bell crank 33, has a pusher finger 35 extending therefrom through a slot 36 in the guard plate 31 and engages the periphery of the coin 30 as it comes to rest on the lug 32. The opposite arm of the bell crank 33 has its extremity resting upon the upper end of the blunt extension 22 and is retained in continual engagement with this extension by a resilient spring 37.

The remaining bulged-out portion 38 of the casing is also provided with a slot into which a key 39 of any conformation is slidably fitted. Said key is provided with a triangular notch 40 in which is engaged the toothed head 41 of a second bell crank 42 which has a longitudinal arm and a short arm. The short arm, in addition to possessing the tooth 41, has a second triangular lug 43 thereon whose cooperation with the rest of the mechanism will be more fully herein-after described. The remaining arm 44 of the bell crank 42 extends vertically downward and is raised to a plane aligned with member 35 and is curved toward the coin at its lower end. The key 39, when inserted in the slot and in the position in which the tooth 41 is engaged in the triangular notch 40, comes into contact with a projection lever 45 which is pivoted intermediate its length and has a pointed upper end 46. The lower end of the lever 45 is engaged by a spring 47 which urges the lower end of the lever to a superimposed position and in contact with the face of the blunt extension 22.

The device serves as a rack upon which may be hung a hat, an article of apparel, such as a coat or a top-coat, a cane and a traveling appurtenance such as a valise or trunk, if the latter can be conveniently supported. This device is adapted to lock these stated articles in place upon the depression of the curved tongue 17. The mechanism permits the opening of the device by a coin-operated means, which coin when dropped into the device, will project a key partly out of the mechanism so that it can be readily removed and, again, upon inception of this key, the locking mechanism is released so that the articles may be removed and worn or carried away.

A hat is suspended from the support arm 15 when the curved tongue is in the position shown in broken lines in Figure 2. The coat or top-coat is suspended from the studs 12 and 13. The cane is placed between the separated studs 12 and 13, and the valise or other traveling commodity is hung from the chain 27. The most convenient link of this chain is then inserted into the opening in the fork 25 which is suitable to permit the inception of one of the links and, upon depression of the curved tongue 17 to the po-

sition shown in full lines in Figure 2, the prong 24 enters into the loop of the link captured in the fork and thus secures this chain in a locked loop. This support arm 15 may only be moved after the coin has been inserted into the slot.

The locking mechanism and key projection means operate in the following manner: The coin is deposited in the slot 29 and falls into and follows the guide plate, dropping adjacent the latter and coming to rest upon the lug 32 immediately in front of the pusher finger 35. The locking device then becomes operable and functions simultaneously with the depression of the curved tongue 17. As the curved tongue is lowered, the blunt head 22 is shifted from an angular position to the position shown in Figure 2. During this movement, the pusher finger 35 engages the periphery of the coin 30, urging this coin across the casing for a short distance. As soon as the coin begins to move it engages the curved lower end of the lug 32 of the bell crank 42, rotating this bell crank until a position is reached where the coin has no further support on the lug 32. When this position is reached, the coin drops into the coin receptacle located conveniently at the lower end of the casing and the short arm of the bell crank 42 is raised to a position where the tooth 41 is released or lifted with the triangular notch 40, thus releasing the key. As the face of the blunt extension 22 assumes a vertical position, the lower end of the lever 45 is projected and superimposed over this extension, locking the same. This movement of the lever is accomplished by the spring 47 in a snappy motion, and the upper sharp end 46 of the lever 45 being in contact with the key 39 will, through the medium of the spring, project said key partly outward until the sharp end of the lever comes into engagement with the member 43 on the bell crank in which position the lever 45 is locked in released position. When the lever 45 assumes the released position shown in Figure 4 the key has been projected, the bell crank has been tripped and the tongue 17, lug 20 and prong 24 are now in locked position as the lower end of the lever 45 is projected over member 22, as shown in Figure 4, and the articles of apparel mounted on the leg are then securely locked against marauders. When desiring to release this locking device for removing the articles from the rack, the key is re-inserted into its particular slot. This key will contact with the tooth 41 raising the same, raising the bell crank against the spring 48, and permitting tripping of the lever. This lever, as the key is farther injected into the slot, is rotated from the position shown in Figure 4 to the position shown in Figure 3. Additional insertion of the key causes the notch 40 thereon to again engage with the

tooth, the spring 48 thereafter urging said bell crank into engaging position with the key in which the tooth 41 falls into the notch and the key then is locked intact in the device, the mechanism being then ready for renewed operation.

It is to be noted that certain changes in form and construction may be made without departing from the spirit and scope of the invention.

10 I claim:

In a device of the class described, a casing, a support arm formed on said casing, a curved tongue pivoted on said support arm and adapted to contact with the extremity of said support arm, a leg unitary with said tongue, studs rising from said casing adapted to contact with said leg, means for locking said tongue and leg in contacting position with the studs and extremity of the support arm, key-operated means for releasing said tongue and leg from engagement with said support arm and studs, means for locking a chain anchored in said casing, a prong on said leg, and means rigid on said casing cooperating with said prong for locking said chain in looped formation.

15 In testimony whereof I affix my signature.

KURT REINHOLD.
